UNITED STATES PATENT OFFICE.

OLIVER WARREN JOHNSON, OF OAKHARBOR, OHIO.

CAR-REPLACER.

SPECIFICATION forming part of Letters Patent No. 717,862, dated January 6, 1903.

Application filed April 15, 1902. Serial No. 103,032. (No model.)

To all whom it may concern:

Be it known that I, OLIVER WARREN JOHNSON, a citizen of the United States, residing at Oakharbor, in the county of Ottawa and State of Ohio, have invented certain new and useful Improvements in Car-Replacers; and I do hereby declare the following to be a full, clear, and exact description of the invention, such as will enable others skilled in the art to which it appertains to make and use the same.

This invention relates to devices for replacing derailed cars or like carriers upon tracks when displaced from any cause.

The purpose of the invention is the provision of a replacer which will embody in its construction a minimum amount of metal, thereby enabling the machine to be readily handled, and which at the same time will be sufficiently strong and durable to withstand the strain and wear incident to its use, the device being braced and stayed from every point.

In its general form the replacer is tapering and elongated and longitudinally curved, the larger base having a slot extended inward therefrom to receive the rail when the device is in position and the smaller end being constructed to rest upon the rail. Tie-rods connect the front and rear ends and guards project upward from the side portions to hold the car-wheel in place and direct it to the rail as said wheel moves forward over the device. The surfaces of the device may be plain or corrugated, as desired, the corrugations or flutes extending either lengthwise or transversely of the device, as desired, in order to stiffen and strengthen the same to give the best results.

The improvement also consists of the novel features, structural details, and combinations of the parts, which hereinafter will be more particularly described, illustrated, and set forth in the subjoined claims.

In the drawings hereto attached and forming a part of the specification, Figure 1 is a top plan view of a car-replacer embodying the invention. Fig. 2 is a side view showing the device applied. Fig. 3 is a rear view. Fig. 4 is a front view. Fig. 5 is a detail view of a tie-rod. Fig. 6 is a section about on the line X X of Fig. 3 looking to the front. Fig. 7 is a top plan view of a modification. Fig.

8 is a rear view. Fig. 9 is a section on the line Y Y of Fig. 7 looking in the direction of the arrow. Fig. 10 is a transverse section of 55 a further modification. Fig. 11 is a longitudinal section of a modification, showing transverse flutes or corrugations.

Corresponding and like parts are referred to in the following description and indicated 60 in all the views of the drawings by the same reference characters.

The replacer is of tapering form and flares outwardly at its rear end and is provided with a slot 1, extended inward from the rear 65 end a distance to admit of the rear portion of the device resting upon a tie 3 when the machine is in position for use, as shown most clearly in Fig. 2. This slot 1 is of a width to snugly receive the rail 4, to which the replacer 70 may be fitted. The device curves longitudinally, and flanges 5 are pendent from the longitudinal edges to stiffen and brace the structure. A series of tie-rods 6 brace the replacer and extend lengthwise thereof and 75 connect the front and rear portions and form chords to subtend the arc formed by the curved portion of the article. These tie-rods have their end portions passed through openings in the front and rear portions of the replacer, 80 the projecting ends being upset or riveted, as shown most clearly in Fig. 5. A flange 7 extends transversely of the device at its rear end and is sharpened at its lower end, so as to penetrate the tie 3 and prevent longitudinal movement of the replacer when a car-wheel 85 is moving thereover. Guards 8 and 9 project upward from the longitudinal edge portions of the replacer to retain the car-wheel in place. The guard 8 is narrow, whereas the 90 guard 9 is broad and presents a flat surface at its top side. Flanges 10 are pendent from the sides of the slot 1 to embrace opposite sides of the rail 4 and prevent lateral slipping of the replacer. The tie-rods 6 adjacent to 95 the sides of the slot 1 are in line with the flanges 10 and come beneath the same and act jointly therewith to stiffen and brace the machine longitudinally.

In the form shown in Fig. 1 and the detail 100 views thereof the upper surface of the part between the guards 8 and 9 is straight and in a lower plane than the upper edge of said guards. In the form shown in Figs. 7, 8, and

9 the middle portion between the guards is raised, as shown at 11, and grooves or channels 12 and 13 are provided between the edges of the part 11 and the guards 8 and 9 to receive the flange of the car-wheel passing over the device. The transverse flange 7 may be continuous, as shown in Figs. 3 and 4, or may be notched, as shown in Fig. 8, to provide, in effect, a series of teeth, so as to more readily penetrate the tie 3 or other part upon which the rear end of the replacer may rest.

The body of the replacer may be straight or corrugated, the latter construction being preferred when the device is constructed of comparatively thin material in order to give the necessary strength. The corrugations or flutes may extend lengthwise of the device, as shown in Fig. 10, or transversely thereof, as shown in Fig. 11, this being a matter of choice, depending upon the direction in which it is required to stiffen and brace the machine.

The rear corners of the replacer bordering upon the slot 1 are cut away, as shown at 14, to clear the foot of the rail at each side of the web and rest on said foot and admit of the rear of the replacer resting upon the tie. To further prevent slipping of the device, it is provided with a grab-hook 15, pivoted to a rear corner and adapted to engage a side of a tie. This grab-hook may be pivoted to the device in any convenient and substantial manner and may be located upon either side, as desired. It is to be understood that the devices will be provided in pairs—rights and lefts—for use upon opposite rails of a track,

so as to lift corresponding wheels of a truck equally.

Having thus described the invention, what is claimed as new is—

1. A car-replacer deflected between its front and rear ends, and tie-rods connecting said end portions, substantially as set forth. 40
2. A car-replacer of tapering form and longitudinally curved, and tie-rods connecting opposite end portions of the device and subtending the intermediate curved portion, substantially as specified. 45

3. A car-replacer having spaced pendent flanges, and tie-rods connecting opposite end portions of the replacer and coming beneath the said flanges to support the same, substantially as set forth. 50

4. A car-replacer of tapering form and longitudinally curved and having a slot extended inward from its rear end and having pendent flanges at the sides of said slot, and tie-rods connecting front and rear end portions of the device, the tie-rods adjacent to the slot coming beneath the said pendent flanges, substantially as specified. 55

5. A car-replacer having its body portion of comparatively thin material and correspondingly corrugated or fluted upon opposite sides to stiffen and strengthen it, substantially as set forth. 60

In testimony whereof I affix my signature in presence of two witnesses.

OLIVER WARREN JOHNSON. [L. S.]
